CURRENT TRANSFORMER

Application filed March 12, 1930. Serial No. 435,099.

This invention relates to current transformers, and particularly to transformers for use with high frequency measuring instruments, such as those required for measurement of current in radio transmitting systems.

An object of the invention is to provide a transformer whose ratio of transformation may readily be adjusted.

Another object of the invention is the provision of a transformer which will maintain itself in permanent position and adjustment.

Still another object of the invention is to provide a transformer which may be coupled with a circuit without the necessity for opening said circuit.

A further object of this invention is to provide a transformer having few parts and which is easily constructed and applied.

The invention possesses numerous other objects and features of advantage, some of which, with the foregoing, will be set forth in the following description of my invention. It is to be understood that I do not limit myself to this disclosure of species of my invention, as I may adopt variant embodiments thereof within the scope of the claims.

Referring to the drawings:

Figure 1 is an end elevation of the transformer of this invention. One method of connecting an instrument to the transformer is shown diagrammatically in this figure.

Figure 2 is a sectional view, taken on the line 2—2 of Figure 1.

Figure 3 is a view similar to Figure 1, showing diagrammatically a second method of connecting an instrument to the transformer.

Figure 4 is an end elevation of a modified form of the transformer, this modification being primarily adapted for portable or temporary use.

Figure 5 is a sectional view of the transformer shown in Figure 4, the plane of section being indicated by the line 5—5 in Figure 4.

The transformer of this invention is of the toroidal type, in which a conductor which normally forms part of the circuit in which the current is to be measured forms the primary. In general terms it comprises a disk

of insulating material surrounding the conductor and preferably having a groove or seat formed in the periphery thereof. The secondary of the transformer is formed by a helical spring which is stretched into toroidal form around the periphery of the disk, the ends of the spring being preferably releasably held by means secured to the disk and connecting with the terminals of the device. Where the transformer is intended for portable or temporary use, the disk is preferably divided diametrically, and the parts thereof are held together by the resiliency of the spring secondary. The transformer is adapted to conductors of various sizes or diameters by means of split bushings or sleeves, whose inner diameters conform to the size of the conductor. The ratio of the transformer can be changed by removing the spring secondary and substituting one of different diameter or number of turns. Smaller ratio variations may be obtained by means of a contact finger which engages a groove concentric with the periphery of the disk, and contacts with a selected turn of the secondary.

Describing the form of the device which is best adapted for permanent insulation in more detailed terms, a portion of the conductor 6 carrying the current to be measured is shown. Surrounding this conductor is a sleeve 7 which is preferably threaded, and which, when once positioned, may be soldered or otherwise secured in place upon the conductor 6.

A disk 8, formed of high grade insulating material such as boro-silicate glass or "micalex", is mounted on the sleeve 7 and held in place by the lock-nuts 9. A groove or seat 11 is preferably formed in the periphery of the disk.

Secured within the groove is a pair of hooks 12 which connect to terminals or binding posts 13 and 13'. These hooks are placed as close together as is convenient, the hook ends facing each other, and they may be held in position in any convenient manner, e. g., molded or screwed in place.

The secondary winding of the transformer is a helical spring 14, which is stretched into

toroidal form and held by the hooks 12. The spring is shown as seated accurately within the groove 11, but it need not necessarily do this as the groove will position it even though it be larger or smaller in diameter than the groove.

Major variations of transformer ratio may be made by removing one spring and substituting another of different diameter or 10 number of turns, or both. Means are provided, however, for effecting minor ratio changes without changing windings. A recess 16, preferably undercut as shown, is formed in a face of the disk 8 concentric with 15 its periphery. A contact finger 17, preferably of spring material, hooks into this recess and extends over the winding. This finger may be moved to contact with any selected turn of the secondary.

20 The meter may either be connected to the terminals 13 and 13', as are shown in Figure 1, or it may be connected to the terminal 13 and a terminal 19 mounted on the contact finger.

25 For temporary or portable use the modification shown in Figures 4 and 5 is advantageous. In this case a split sleeve or bushing 26 is used, a plurality of these bushings of varying internal diameter being preferably 30 provided to fit different sizes of conductors. The disk in this case is formed in two halves 27 and 28, and fits closely over the divided sleeve 26. The hooks 29 and 31 are both mounted on the half 28 of the disk, and when 35 the spring 32 is stretched in place its resiliency holds the parts of both disk and bushing in position. Minor adjustments in ratio are made with the contact finger 33 which engages the recess 34 in the same manner as 40 in the other modification of the device.

Although the latter modification does not have the advantage of permanency to the same extent as the first form described, the split parts may be applied to any conductor 45 without opening the circuit of which it forms a part, and it is therefore of value in taking test readings in circuits where the permanent installation of an instrument is not warranted. The formation of the parts 50 is such that the spring tension of the secondary serves to align the device accurately perpendicular to the conductor.

It is obvious that the transformer will 55 operate even though the disk may depart materially from circular form. The advantage of the circular shape lies in its economy of space and material, and in the ease of computation of the transformer ratio. It is to be understood however, that supporting members of other shapes are equivalents of the circular disk if used as here described.

I claim:

1. A current transformer comprising a conductor forming a primary, an insulating disk mounted on said conductor, and a helical

spring forming a secondary stretched in toroidal form about said disk.

2. A current transformer comprising a conductor forming a primary, an insulating disk mounted on said conductor, a helical 70 spring forming a secondary stretched in toroidal form about said disk, and means on the disk for releasably engaging the ends of said spring.

3. A current transformer comprising a 75 conductor forming a primary, an insulating disk mounted on said conductor and having a seat formed in the periphery thereof, and a helical spring forming a secondary stretched in toroidal form about said disk and positioned by said seat.

4. A current transformer comprising a conductor forming a primary, an insulating disk mounted on said conductor and having a recess concentric with the periphery formed 85 in a face thereof, a resilient toroidal secondary stretched around said disk, and a contact finger engaging said recess and adjustable to contact with a selected turn of said secondary.

5. A current transformer adapted for use with a current-carrying conductor comprising a sleeve adapted to fit over the conductor, an insulating disk mounted on said sleeve, and a resilient toroidal secondary stretched 95 around the periphery of said disk.

6. A current transformer adapted for use with a current-carrying conductor comprising a divided disk adapted to surround said conductor, and a helical spring forming a secondary winding and stretched around said disk to hold the parts thereof in position.

7. A current transformer adapted for use with a current-carrying conductor comprising a divided disk adapted to surround said conductor, and a helical spring forming a secondary winding and stretched around said disk and secured to one of the parts thereof to hold the parts in position.

8. A current transformer adapted for use 110 with a current-carrying conductor comprising a split sleeve having an inner dimension adapted to fit over said conductor, a divided disk fitting over said sleeve and perpendicular thereto, and a helical spring stretched in 115 toroidal form around said disk and forming a secondary for said transformer and holding the parts of said disk in position.

9. A current transformer adapted for use with a current-carrying conductor comprising a split sleeve having an inner dimension adapted to fit over said conductor, a divided disk fitting over said sleeve and perpendicular thereto, a helical spring stretched in toroidal form around said disk and forming a secondary for said transformer and holding the parts of said disk in position, and means on 120 one of the parts of said disk for releasably engaging the ends of said spring.

10. A current transformer comprising a 130

conductor forming a primary, an insulating disk mounted on said conductor, a helical spring forming a secondary stretched in toroidal form about said disk, means on said disk for releasably holding an end of the spring, and a terminal for said secondary connected to said holding means.

5 In testimony whereof, I have hereunto set my hand.
